APPARATUS FOR SPINNING
ARTIFICIAL SILK

Hans Alwin Schrein, Arnhem, Netherlands, assignor to American Enka Corporation, a corporation of Delaware

Application November 29, 1933, Serial No. 700,290
In Germany March 25, 1933

2 Claims.

(Cl. 18—8)

The present invention relates to spinning and collecting filaments or threads of artificial silk, such as artificial silk coagulated or precipitated from viscose or solutions of cellulose, for example solutions of cellulose in cuprammonia and other solvents.

Among the objects of the invention is the provision of a process for spinning artificial silk according to the so-called spool system or process in which the freshly spun or coagulated artificial filament or thread is wound on a spool or other carrier with desired adjustable and substantially constant tension.

A further object of the invention is the provision of a process for forming and winding artificial silk prepared from viscose, cuprammonia solutions of cellulose, and similar cellulosic solutions, in which the cellulosic solutions are coagulated or precipitated as thread or filaments and thereafter, without drying the latter, winding them on a spool or other carrier which is so driven as to permit the thread or filaments to exert a braking or retarding action upon the rotation of the spool or other carrier.

According to the present invention the tension of the filaments or thread being wound upon the spool or other carrier is maintained completely constant by elastically or yieldingly applying power in rotating the spool or other carrier. This is accomplished by placing between the spool or spool holders and the source of power for driving the spool, or spool holders, power transmitting means which permits braking of the spool by the thread being wound even with small rise in tension.

In using such an elastically or yieldingly driven winding means it is expedient to place before the spool a positively driven drawing-off means or wheel, for example a godet, by means of which the filaments or threads are supplied with constant velocity and without slip. For avoiding slip, the filaments or thread can be wound several times around the drawing roller. In addition, tensioned or elastically yielding filament or thread guides may be arranged between the drawing-off means and the winding spool for equalizing tension differences or for securing of a certain minimum tension.

A still further object of the invention is the provision of a spinning process and apparatus for artificial silk prepared from materials as above described in which the spool on which the threads or filaments are wound, or the holders on which said spools are carried, are each driven

through a slipping or friction clutch, or slipping connection from a suitable source of power.

The slipping or friction connection according to the adjustment of its slipping or friction moment permits only a definite driving moment to be transmitted. The moment of the filaments or thread tension stands in equilibrium with this driving moment, whereby the tension of the filaments or thread upon being wound on the spool is adjustable. The velocity of winding must be constant on account of the constant supply of thread or filaments. This is rendered possible since the driving takes place through a slipping clutch or connection, whereby the number of revolutions of the spool can become correspondingly less as the diameter of the windings increases. As slipping or friction clutches or connections, the following are suitable for use: dry or lubricated slipping clutches, hydraulic, pneumatic or magnetic couplings or clutches.

In the drawings in which the invention is illustrated,

Figure 1 is a schematic view of one arrangement of apparatus.

Figure 2 is a schematic view showing a modified arrangement of apparatus.

Figure 3 is a central longitudinal section of the holder or carrier for the spool on which the filaments or threads are wound, and in which the yielding or slipping connection is a slipping or sliding clutch.

Figure 4 is a side elevation, partly in section of another modification of apparatus for practicing the invention.

Figure 5 is a cross-section on the line 5—5 of Figure 4.

Figure 6 is a yielding thread or filament guide, partly in section, which may be employed in practicing the invention.

Figure 7 is a central vertical section of another modification of thread tensioning means.

Figure 8 is a section on the line 8—8 of Figure 7.

Figure 9 is a schematic view of apparatus for practicing the invention utilizing the elastic or tensioned thread guide shown in Figures 7 and 8.

Figure 10 is a schematic view of apparatus for practicing the invention utilizing the tensioning means for the thread or bundle of filaments shown in Figure 6.

Figures 11 and 12 are respectively a plan and a side elevation of a modification of tensioned or elastic thread guide.

Figure 13 is a plan, partly in section, of another modification of thread guide.

Referring to Figure 1, the numeral 1 indicates a nozzle or spinneret for the viscose or other cellulosic solution; and 10 the coagulating or precipitating bath. The filaments or threads 11 pass under the guide rod 12 and then over and around the uniformly and positively driven drawing-off roller 2. The filaments or threads are wound one or more times around the drawing-off roller or godet wheel 2 and guide 14 to prevent slipping. By drawing-off the filaments free of slip, the supplied quantity of filaments remains constant. From the roller or wheel 2 the filaments are conducted into a bath or plurality of baths 3, where the filaments or threads 15 may be treated further with coagulating agents, washing agents, desulphurizing agents, bleaching agents or other agents used in manufacturing artificial threads or filaments. The threads or filaments pass under the guide 16 submerged 20 in the liquid of bath 3; and, after leaving the bath 3, are wound upon the spool 4. If desired, the bath or baths 3 may be omitted, and the threads wound on the spool 4 without pretreatment; and in this latter event a guide 16 is 25 preferably employed before the spool or bobbin 4. Traversing thread or filament guides are indicated at 15 for the purpose of distributing the thread over the surface of the spool 4.

The spool or bobbin 4 is not fixed or rigidly attached to the spool driving shaft 5, but between the spool and the driving shaft is positioned a sliding or slipping clutch diagrammatically indicated by the numeral 6, the slipping of which varies with the thread or filament tension and permits only a definite or fixed driving moment to be transmitted to the spool 4.

It is to be understood that between the spinning nozzle 1 and the drawing-off roll 2, as well as between the drawing-off roll 2 and the spool 4, the threads or filaments may be subjected to various treatments, such as stretching and intermediate treatments with liquid treating agents.

The sliding or slipping clutch shown in Figure 3 is an example of a clutch and spool holder construction which may be used in practice and diagrammatically indicated at 6 in Figure 1. Referring specifically to Figure 3, A indicates a positively driven shaft of the spinning machine and on this shaft is positioned the holder B for the spinning spool C. The spool C is preferably made of metal and perforated. The shaft A in Figure 3 corresponds with the shaft 5 in Figure 1.

The spool holder B has an accessory part 1a provided with a set screw 2a for attaching it to the drive shaft A. With the accessory part 1a is connected the threaded bolt or stem 3a which is provided with a fixed cone 4a and a cone 5a capable of being screwed along the bolt or member 3a. The cone 5a is made secure in position by means of a jam or lock nut 6a. The cones 4a and 5a serve as abutments or races for the two ball bearings 1a and 8a of the hub 9a.

With the hub 9a is connected the true spool holder 10a, which with the screw threaded piece 11a forms a joint body. The spool holder 10a surrounds the shoulders 12a and 13a of the hub 9a as shown in Figure 3. Its connection with the hub 9a is rendered possible by means of the flange or securing means 14a which is clamped by the screw piece 11a between the latter and the spool holder 10a.

On a pin or extension 15a of the bolt 3a is placed a plate 16a which can freely move longitudinally back and forth along the extension

15a, but which is secured against turning relative to the extension 15a and the member 3a by means of a screw 17a which slidably engages within a groove of the extension 15a. The plate 16a is pressed against a friction surface 19a on 5 the member 11a by means of a spiral spring 18a positioned about the extension 15a. The numeral 20a indicates a lubricating cap or an inlet for lubricant. The plate 16a is provided with a friction or sliding surface which engages the 10 corresponding friction or sliding surface 19a.

The accessory part 1a is provided with a beveled portion 21a which fits within a correspondingly beveled portion 22a of the spool holder 10a. A circular ridge 23a is provided on 15 the spool holder 10a adjacent the part 1a. The parts of the device are so dimensioned that, when assembled, the part 1a and its beveled surface 21a are normally out of contact with the spool holder 10a. The purpose of the ridge 23a is to 20 reduce friction between the part 1a and the spool holder 10a as much as possible when the parts of the device become worn by use, and to this end the ridge 23a is sufficiently high to contact with the inner end of the part 1a in a bearing 25 relationship before the beveled surfaces 21a and 22a contact with each other.

A rubber or elastic ring 24a is placed or stretched over the spool holder 10a and is adapted to fit in spaced circular depressions 25a 30 and 26a surrounding the spool holder 10a. The purpose of the ring 24a is to attach or fasten the perforated spool C, upon which the threads or filaments are wound, to the spool holder 10a. The perforated spool C is shown attached to the 35 holder 10a in Figure 3. The external diameter of the ring 24a is somewhat larger than the internal diameter of the spool C so that the ring 24a is compressed between the spool C and the spool holder 10a when the spool C is pushed on 40 the holder 10a. As a result, the spool C will be held for rotation with the holder 10a. When the spool is pulled off the holder, the rubber ring rolls upon the surface 21a and thereafter into the depression 26a; then when a new spool is 45 pushed over the holder the rubber ring 24a rolls back to the depression 25a in a similar manner. This construction greatly facilitates effectively attaching the spool to the holder and detaching it therefrom. It will be readily understood that 50 the spool C in Fig. 3 corresponds with the spool 4 in Figure 1.

In Figure 2 which shows a modified arrangement of apparatus, 1b denotes the spinneret; 10b, the coagulating bath; 12b, a guide rod; 2b, the positively and uniformly driven drawing-off roll or godet wheel; 17b, a pulley or guide rod; 20b, a positively and uniformly driven stretching roll; 16b, a guide rod submerged in the after treating bath or baths 3b; 4b, a spool on which 60 the threads or filaments are wound; 6b, a friction clutch, for example as shown in Figure 3; 5b, a positively driven drive shaft; 15b, a thread guide reciprocating before the spool 4b for distributing the thread 11b over the surface of the 65 spool 4b. The stretching roll or wheel 20b is driven at a greater peripheral speed than the drawing-off roll 2b in order to produce stretching between the drawing-off roll 2b and the roll 20b. The filaments 11b follow the path shown in the 70 drawings. The filaments may be wound one or more times around the godet wheel 2b and may simply pass over or may be wound one or more times around the positively driven roll 20b. The after treating baths in the arrangement of ap- 75

paratus shown in Figure 3 may be eliminated, and the thread or filaments spooled without the use of after treating baths or liquids.

In Figures 4 and 5 is shown a modification of the invention in which the driving of the spool or bobbin is accomplished by means of an air turbine driven by compressed air. In these views 30 indicates a plurality of shafts to which the turbines 31 are attached at one end; and 10 at the opposite end of each shaft is attached a spool holder 32 which detachably carries the spool 33. Only one spool holder and spool shown for the purpose of simplifying the drawings. The shafts 30 are supported in ball bearings as shown. The pipe 34 carries compressed air to the turbines 31 for driving the latter and the shafts 30. The pipe 34 has two branches 35 and 36, each of which are again branched as shown in Figure 5.

20 In practicing the present invention it has been found that it is advantageous to equalize the filament or thread tension on the part of the filaments or thread before the spool, on which the filaments or threads are wound, by means of an elastic or elastically mounted thread guide, for example elastically or yieldingly mounted hooks or small rolls. The advantages of this mode of operation consist in this that a more rapid or energetic traverse of the thread in 25 spooling can be employed, that is to say, a quicker reciprocating movement of the thread guide before the spool can be used. Besides, in this case, the tension of the thread or filaments can be less. Examples of suitable elastic or yielding 30 thread guides and their use for this purpose are shown in Figures 6, 7, 8, 9, 10, 11, 12, and 13.

Referring to Figure 9, 1c indicates the spinneret; 10c, the coagulating or precipitating bath; 40 12c, a thread guide; 2c, a positively and uniformly driven drawing-off roll or wheel around which the filaments or threads may be wound one or more times; 3c, after treating bath or baths; 4c, the spool or bobbin on which the filaments or threads are wound; 5c, a shaft positively driven from any suitable source of power; 6c, a friction or slipping clutch, for example, as shown in Figure 3, placed between the drive shaft 5c and the spool 4c; 15c, a thread guide reciprocating 45 before the spool 4c to distribute the filaments or thread over the surface of the spool. As shown in Figure 9, the threads or filaments 11c pass from the spinneret through the coagulating bath, then under the guide 12c to the drawing-off roll 2c. From the drawing-off roll 2c the thread or filaments pass under the hook portion of the thread guide 16c, the details of construction of said thread guide being shown in Figures 7 and 8 on larger scale than in Figure 9. The thread or filaments pass from the thread guide 16c to the winding spool or bobbin 4c.

60 The thread guide shown in Figures 7, 8 and 9 comprises a cylindrical portion 30c made of cork, or other suitable light material, and is traversed longitudinally by an opening 31c. Attached to the cork portion 30c about midway of its ends is a porcelain hook 32c under which the filaments or thread 11c pass, as shown in Figures 7, 8 and 9. Through the opening 31c is passed a slender elastic or rubber band 33c. The free ends of the elastic or rubber band are advantageously joined together so as to form a closed band passing through the opening 31c. In use 70 the rubber band is engaged within spaced hooks

34c and 35c attached to the bottom of the treating bath 3c, so as to enable the hook 32c to be held below or above the surface of the liquid of the after treating bath 3c. In Figure 7 the rubber band 33c is long enough to permit the 5 thread 11c to pass under the hook 32c above the surface of the liquid of the bath 3c, which construction is used when it is not desired to submit the threads or filaments to the action of the bath 3c. However, in Figure 9 the rubber band 33c has been shortened to cause the hook 32c and the thread or filaments 11c to be submerged in the liquid in the bath 3c in order to accomplish after treatment of the threads or filaments. This shortening may be accomplished 10 in any suitable manner, for example, by winding the rubber band around the hooks 34c and 35c until the desired shortening is produced. The cork 30c imparts buoyancy to the hook 32c 15 in the liquid of the treating bath.

20 In the modified arrangement of apparatus shown in Figure 10, 1d indicates the spinneret; 10d, the coagulating or precipitating bath; 12d, a thread guide, 2d, a positively driven drawing-off roll or godet wheel; 16d, a thread guide 25 shown in Figure 6; 4d, a spool or bobbin on which the filaments or threads 11d are wound; 15d, a guide for distributing the thread or filament on the spool or bobbin 4d; 5d indicates a drive shaft driven from any suitable source of 30 power; and 6d indicates a slipping clutch or yielding driving connections, for example, as shown in Figures 3, 4 and 5. The thread guide 16d comprises a long piece of cork 40d (see Figure 6), for example in the shape of a rod, to the 35 top end of which is secured a porcelain hook 41d under which the thread or filament 11d passes on its way to the bobbin 4d as shown in Figure 10. The cork body constitutes a float and is weighted at the lower end by means of 40 a small body of lead 42d (see Figure 6). The thread guide shown in Figure 6 is used as shown in Figure 9. It is placed in a container 43d in which water is placed, the depth of the water being sufficient to permit the device to float. 45 The mass of lead 42d maintains the device upright. As the tension on the thread 11d increases the device is pulled further out of the water and hence pulls harder against the thread passing under the hook 41d.

50 The thread guide shown in Figures 11 and 12 comprises a corrosion resistant wire arm 50, coiled in the form of a spring 51 at the end adapted to be connected with supporting means and bent at right angles at the opposite end to 55 receive a pulley or grooved roller 52. Stop means 53 and 54 are fixed on the wire on each side of the roller 52 to hold it in proper position.

The thread guide shown in Figure 13 comprises a rod 60 which is joined to a stud 61 on a suitable supporting means by means of a piece of rubber or elastic tube, the rod 60 being spaced somewhat from the stud 61 as shown in the drawings. At the opposite end of the rod 65 60, which may be made of glass or metal which resists corrosion, is secured the pulley or grooved guide roller 62. The roller 62 is advantageously carried on an extension 63 attached to the rod 60 by any suitable connection, indicated by the 70 numeral 64. Retaining means 65 and 66 are used on the extension 63 for retaining the roller 62 in operative position.

The thread guide means shown in Figures 11, 12 and 13 may be used as substitutes for the 75

thread guide means **16**, **16b**, **16c**, and **16d** shown respectively in Figures 1, 2, 9 and 10.

I claim:

- 5 1. An apparatus for spinning artificial silk filaments comprising in combination, a spinnerette, a bath for coagulating the filaments, a drawing off roller for drawing the filaments from the spinnerette and through the coagulating bath, a rotatable collecting device for winding the 10 filaments thereon, and means for regulating the tension imposed upon the filaments during the

winding operation which includes a flexible thread guide interposed between the drawing off roller and collecting device, and a slipping clutch operative between the collecting device and a source of power.

- 5 2. A flexible thread guide for use in the manufacture of artificial silk which comprises a flexible arm having a roller attached to one end thereof, said arm being freely oscillatable in any direction.

10 HANS ALWIN SCHRENK.
